UNITED STATES PATENT OFFICE.

JAMES S. TIERNEY, OF BROOKLYN, NEW YORK, ASSIGNEE TO AMERICAN SHOP EQUIPMENT CO., OF CHICAGO, ILLINOIS, A CORPORATION OF MAINE.

FURNACE.

1,269,132.

Specification of Letters Patent. Patented June 11, 1918.

Application filed February 6, 1917. Serial No. 146,819.

To all whom it may concern:

Be it known that I, JAMES S. TIERNEY, a citizen of the United States, residing at Brooklyn, in the county of Kings and State 5 of New York, have invented a new and useful Improvement in Furnaces, of which the following is a specification.

My invention relates to improvements in furnaces employing oil as fuel such as crude 10 petroleum or any other suitable fuel oil.

It is highly desirable in furnaces employing oil as fuel, especially where metallic bodies are subjected to heat therein, that provision be made for producing perfect 15 combustion of the fuel before it reaches the heating chamber, in order that heated gases only, as distinguished from gases containing uncombined carbon or oxygen, enter the heating chamber, and furthermore that the 20 furnace be so constructed that this effect may be accomplished by as compact a structure as possible not only because of the saving in expense in constructing the furnace but also because of the economizing of the 25 space occupied by the furnace.

A furnace in which the above referred to features are presented and the above referred to results are accomplished, is illustrated and described in U. S. Letters Patent 30 1,130,306 granted to Waldo G. Lunger, March 2, 1915, and while this furnace operates very effectually under normal conditions of use, it has been found that where the furnace is operated to its maximum extent, it becomes overheated to an objectionable degree, sometimes burning out the furnace.

My object is to provide a novel, simple, economical, compact and highly serviceable 40 construction of furnace of the general type illustrated in said Letters Patent and which will operate in the manner above described and by which the full benefit of the heat units in the fuel may be obtained.

45 It may be further stated that in the furnace of the said patent wherein the streams of air, one or both of which carry a stream of fuel oil, are directly opposed in the sense that the streams of air are in alinement with 50 each other, the effect is to cause a more or less disk shaped body of flame to be thrown out in all directions in a vertical plane at the juncture of the opposed streams, the marginal edges of this body of flame being 55 intensely hot. This body of flame projects

in one direction against the rear wall of the initial combustion chamber and at its opposite edge extends toward the heating chamber impinging against the upper and lower walls of the passage leading to the heating 60 chamber, at which walls the maximum heat of the furnace obtains, the flow of burning gases to the heating chamber to perform the function of heat treating the materials to be operated on in the furnace, being effected 65 at least principally by the expansion of the gases which in acting against the rear wall of the furnace cause burning gases to flow into the heating chamber. As a consequence the burning gases are retained in the primary 70 combustion end of the furnace an undue length of time, causing the furnace to be unduly subjected to heat and, by reason of pushing, so to speak, against the rear wall of the primary combustion chamber are 75 caused to eddy in this chamber wherein carbon is accumulated sometimes to an objectionable degree; and one of my objects is to avoid the occurrence of such conditions.

Referring to the accompanying drawings: 80

Figure 1 is a view in horizontal plan section of a furnace constructed in accordance with my invention, designed for heating metallic bodies therein, the section being taken at the line 1 on Fig. 2 and viewed in the 85 direction of the arrow.

Fig. 2 is a section taken at the line 2 on Fig. 1 and viewed in the direction of the arrow;

Figs. 3 and 4 are sections taken at the 90 lines 3 and 4 respectively on Fig. 2 and viewed in the direction of the respective arrows; and

Fig. 5 is an enlarged broken sectional view taken at the line 5 on Fig. 2 and viewed 95 in the direction of the arrow.

In constructing a furnace in accordance with the preferred embodiment of my invention, where metallic bodies are to be subjected to heat, I provide a heating chamber, represented at 6 into which the articles to be treated by the heat are introduced as through the opening 7 in a side wall of this chamber. Opening into the heating chamber 6 is a passage 8 which preferably 100 widens out at its end farthest from the chamber 6 as indicated at 9, the rear wall of this passage being three sided as represented at 10, 11 and 12, the side 11 being substantially at right angles to the median 105 110

line of the passage 8 and the sides 10 and 12 extending preferably at equal angles to the said median line and converging rearwardly, the angle at which these two walls extend 5 relative to each other being slightly less than a 90° angle and which has been found to be desirable construction in practice. The forward edges of the walls 10 and 12 are located at the broadest portion of the passage 10 8 and from these points the walls of the latter converge for a slight distance as by providing them of the rounded contour as shown at 13.

The furnace is formed of refractory material, such as fire brick suitably positioned to present the chamber and passage referred to, the whole being incased in a metal shell 14.

As will be hereinafter more fully explained the greatest heat produced by the introduction of fuel into the furnace as hereinafter described occurs in the passage 8 wherein all of the oil is volatilized, and this has led to the formation of the body of 25 the furnace of such construction that should the intense heat in this part of the furnace burn out the roof of the passage 8, it may be readily repaired at relatively slight expense, very quickly, and without tearing 30 down a substantial part of the furnace. This is accomplished in the construction illustrated by supporting the roof 15 of the heating chamber 6 and which is shown in the form of an arch, from a block 16 35 which bears at its opposite ends upon the sections 17 and 18 of the end wall 19, the wall 19 being recessed as indicated at 20 between the portions 17 and 18 at opposite sides of the passage 8, to receive a block 21 40 of refractory material, which merely serves as a roof for the chamber 6 and which may be readily removed without disturbing the superposed parts of the structure, in the event that it is desired to replace it with 45 another block. The roof of the passage 8 at the left hand side of Figs. 1 and 2, or in other words beyond the wall 19, is formed of a block or slab 22 which is merely set into place and which may be readily removed 50 to permit of the removal of the block 21 through this end of the furnace.

Opening into the enlarged portion 9 of the passage 8, through the walls 10 and 12, and preferably at substantially equal distances from the top and bottom of the passage 8, are pipes 23 and 24 which communicate with an air supply. These pipes 23 and 24 are so arranged as shown that they incline at an angle to each other slightly 55 greater than 90° and each is equidistant from and extends substantially at the same angle to the median line of the furnace, the purpose being, as hereinafter more fully described, to cause jets of air introduced 60 into the passage 8 through the pipes 23 and

24 to impinge against each other with substantially equal force. In the construction illustrated the pipes 23 and 24 open into a valve casing 25 containing a valve 26 which communicates at its open end 27 with a pipe 70 28 leading from any suitable source of air under pressure, and communicates with the pipes 23 and 24 through ports 29 and 30 respectively, the parts described being so proportioned that they will operate to cause 75 equal quantities of air to pass from the pipe 28 into the pipes 23 and 24, so that the air passed into the furnace from the pipe 28, through the pipes 23 and 24, will enter the passage 8 from opposite sides thereof in 80 substantially equal proportions.

The fuel oil is introduced into the passage 8, according to my invention, through either one or both of the pipes 23 and 24. In the construction illustrated, provision is made 85 for introducing the oil into the furnace through both of the pipes 23 and 24, and to this end pipes 30, adapted to be connected with a source of supply of any suitable fuel-oil, and preferably having a needle-valve- 90 controlled discharge-orifice, project into the pipes 23 and 24 in line therewith, it being preferred that the supply of oil with which the pipes 30 are connected be under a pressure sufficient to feed the oil in the proper 95 amounts as conditions require.

It is desirable in carrying out my invention in the preferred manner, to cause the fluid under pressure entering the passage 8 through the pipes 23 and 24, to be under 100 substantially equal pressure in these pipes, which will cause the streams of fluid under pressure entering the passage 8 from opposite directions, to impinge against each other at a point substantially midway between the side walls of the passage 8.

The operation of the furnace in so far as the construction has been described is as follows: Assuming the valve 26 to be open, air will enter the passage 8 at opposite sides 110 thereof, through the pipes 23 and 24, the air in passing through these pipes atomizing the oil from the pipes 30 and becoming mixed therewith. The oil is ignited for lighting the burners in any suitable manner, 115 as by introducing burning waste into the passage 8.

The effect of opposing burning streams of oil and air mixed therewith, or a burning stream of oil and air and a stream of air 120 only, with these streams converging in a direction toward the heating chamber and causing these opposed streams to impinge against each other, is to not only thoroughly mix the oil and air, but also to produce such 125 retarding of the burning oil that it will be thoroughly volatilized before reaching the heating chamber 6 and thus will be free of uncombined oxygen and carbon upon entering the heating chamber, and at the same 130

time the converging relation of the streams introduced into the passage 8 from the pipes 23 and 24, causes the burning oil, by reason of the fluid under pressure issuing from these pipes, to be forced in a direction for entering the heating chamber, as distinguished from the forcing of the gases into the heating chamber by expansion only of the gases. Furthermore by causing the streams to impinge against each other at an angle the back-eddying of gases, with consequent accumulations of carbon in the passage into which the fuel is introduced, is avoided.

15 In building a furnace in accordance with my invention, I am enabled to produce a structure of the maximum compactness from a commercial standpoint, the movement of the burning oil through the passage 20 8 into the chamber 6 being sufficiently retarded by reason of the opposed streams entering the passage 8 to insure the volatilization of the oil before it enters the chamber 6, even where the passage 8 is relatively short. In addition to the advantages hereinbefore stated, which arise from the angular disposition of the streams of fluid under pressure entering the passage 8, it may be stated that the vertical dimension 25 30 of the mass of flame presented by the united streams, is considerably less than where the streams are in direct line with each other as in the case of the said patent, and thus the upper and lower walls of the passage 35 leading to the heating chamber, are not subjected to as intense heat as in the case of the construction of the said patent.

It is desirable, in connection with a furnace structure employing streams of fluid 40 under pressure one or both of which carry oil and which impinge against each other and in so impinging unite and form a mass of flame, that means be provided for protecting from the heat, as far as possible, 45 the walls of the passage through which the united stream passes and which are transversely disposed to the plane of the greatest dimension of the stream. Means suitable for this purpose are disclosed in the drawings, these means comprising inlets 31 and 50 55 32 in the rear wall 33 of the passage 8, for fluid under pressure, such as air, introduced into these inlets through a pipe 34 leading to any suitable source of air under pressure. 60 The inlets 31 and 32 are preferably of the tapering form shown, their bottom and top walls respectively converging rearwardly where they meet substantially at the point at which the air discharges from the pipe 65 70 75 80 85 90 95 100 105 110 115 120 125 34, whereby the stream of air discharging from this pipe is divided, a part being deflected upwardly and a part downwardly and thus streams of air discharge against the upper and the lower walls of the passage 8, the inlets 31 and 32 where they directly

open into the passage 8 being preferably in the form of narrow horizontal slits as shown in Fig. 4. The air or other fluid under pressure introduced into the passage 8 from the inlets 31 and 32, thus sweeps against the 70 top and bottom walls of the passage 8 and serves to prevent them from becoming heated to as great a degree as they would be if the fluid under pressure were not supplied as stated.

75 While I have shown the pipes 23 and 24 as disposed at a certain angle to each other, I do not wish to be understood as intending to limit my invention to an arrangement wherein these parts are disposed at the angles shown as this is not necessary to the carrying out of the invention; and while I have shown and described my invention as applied to a furnace for subjecting metallic bodies to heat, I do not wish to be understood as intending to limit it to its use in this connection as it may be employed in many other kinds of furnaces without departing from the spirit of my invention, furthermore I do not wish to be understood 80 as intending to limit my invention to the particular form of construction shown, as the same may be variously modified and altered without departing from the spirit of my invention, it being my intention to claim 85 my invention as fully and completely as the prior state of the art will permit.

What I claim as new and desire to secure by Letters Patent is:—

1. In an oil-burning furnace, the combination with a heating chamber for receiving the material to be treated, of means for effecting the complete volatilization of the heating medium before its entry into said chamber, comprising a passage communicating therewith and having an enlarged outer end and a contracted portion leading therefrom with angularly disposed openings in the walls of said enlargement, and means in said openings for feeding streams 100 of air and oil therethrough into said passage to cause said streams to impinge against each other in said enlargement and to converge therefrom into said contracted portion, whereby said streams are retarded 105 in their traverse to the heating chamber and the complete volatilization of the heating fluid is effected before the same enters said chamber.

2. In an oil-burning furnace, the combination of a heating chamber for receiving the material to be heated, an oil-volatilizing passage communicating with said chamber and means for causing streams of air, with oil in either or both thereof, to enter 110 115 120 125 said passage from opposite directions for impingement against each other, and converging in a direction for forcing them through said passage and into said heating chamber, the whole being constructed and

arranged to completely volatilize the oil exterior of the zone occupied by the material, and means for directing fluid under pressure between the united streams and a wall of 5 said passage.

3. In an oil-burning furnace, the combination of a heating chamber for receiving the material to be heated, an oil-volatilizing passage communicating with said chamber 10 and means for causing streams of air, with oil in either or both thereof, to enter said passage from opposite directions for impingement against each other, and converging in a direction for forcing them through 15 said passage and into said heating chamber, the whole being constructed and arranged to completely volatilize the oil exterior of the zone occupied by the material, and means for directing fluid under pressure in 20 the same general direction as that in which said united streams move, between said united streams and a wall of said passage.

4. In an oil-burning furnace, the combination of a heating chamber for receiving the material to be heated, an oil-volatilizing passage communicating with said chamber and means for causing streams of air, with oil in either or both thereof, to enter said 25 passage from opposite directions for impingement against each other, and converging in a direction for forcing them through said passage and into said heating chamber, the whole being constructed and arranged 30 to completely volatilize the oil exterior of the zone occupied by the material, and means for directing fluid under pressure between the united streams and opposed walls 35 of said passage.

5. In an oil-burning furnace, the combination of a heating chamber for receiving the material to be heated, an oil-volatilizing passage communicating with said chamber 40

and having an enlargement, and means for causing streams of air, with oil in either or both thereof, to enter said enlargement from opposite directions for impingement, against each other and converging in a direction for forcing them through said passage and into said heating chamber, the 45 whole being constructed and arranged to completely volatilize the oil exterior of the zone occupied by the material, and means for directing fluid under pressure between the united streams and a wall of said passage. 50

6. In a furnace the combination of a chamber, a passage in a wall of said chamber and opening into the latter, the roof of said chamber being supported from the 55 said wall, with a recess in said wall and with the roof spanning said recess, and a roof-forming section for said passage located, and supported, in said recess to be removable and replaceable therein. 60

7. In a furnace, the combination of a chamber, a passage communicating with said chamber, means for causing streams of air with fuel in either or both thereof, to enter said passage from opposite directions for impingement against each other and converging in a direction for forcing them through said passage and into said chamber, the wall of said chamber in the 70 rear of the point at which said streams 75 impinge, containing an opening with a bridge at said opening, the upper and lower surfaces of which converge in a direction away from the movement of the streams through said passage, and means for directing fluid under pressure through said opening, whereby the fluid sweeps against the upper and lower surfaces of said passage, for the purpose set forth. 80

JAMES S. TIERNEY.
